UNITED STATES PATENT OFFICE.

HARRY R. WILLIAMS, OF HARTFORD, CONNECTICUT, ASSIGNOR, BY MESNE ASSIGNMENTS, TO EDWARD A. DE BLOIS, OF SAME PLACE.

DESIGN FOR A TROUSERS-HANGER.

SPECIFICATION forming part of Design No. 33,020, dated July 31, 1900.

Application filed June 7, 1900. Serial No. 19,487. Term of patent 3½ years.

To all whom it may concern:

Be it known that I, HARRY R. WILLIAMS, a citizen of the United States, residing at Hartford, in the county of Hartford and State of Connecticut, have invented and produced a certain new Design for Trouzers-Hangers, of which the following is a specification.

Figure 1 of the accompanying drawings illustrates a side view of a trousers-hanger formed according to the new design, and Fig. 2 illustrates a plan view of the same hanger.

As shown in the drawings, the leading or material feature of the design consists of the single piece of rod shaped so as to form a number of substantially-parallel sections 1, lying at a distance from each other in the

same plane and joined each with the next alternately at opposite ends by curved sections 2, and a pair of parallel sections 3, lying contiguous to each other in the same plane, but at right angles to the plane of the open sections, the closed sections being joined by curved sections 4 at the opposite ends.

Having now particularly described my invention, what I claim as new, and desire to secure by Letters Patent, is—

The design for a trousers-hanger herein shown and described.

HARRY R. WILLIAMS.
